INVENTOR:
CHARLES W. FAWCETT,

BY J. H. Cook
ATTORNEY.

UNITED STATES PATENT OFFICE

2,123,410

AIR DUCT

Charles W. Fawcett, St. Louis, Mo.

Application April 9, 1937, Serial No. 135,875

1 Claim. (Cl. 20—92)

My invention relates to a new and useful improvement in air ducts, and has for its object to provide a simple, inexpensive, and highly satisfactory medium for attaching together the 5 plaster board members of the air duct so that a continuous duct is provided through which a column of air may flow from one point to another. Such air ducts are usually rectangular in cross-section, and may consist of two, three, 10 or four walls of plaster board, the other wall or walls being formed by the partition wall or the ceiling of the building in which the air duct is located. My invention is equally applicable where plaster board is employed in any or all 15 such walls.

Another object is to provide a simple means for securing the air duct to the wall or ceiling where the wall or ceiling, or both, comprise one or more of the walls of the duct. By my arrangement a lightweight air duct structure is formed, and one which can be easily and economically constructed.

Fig. 1 is a perspective view of a length of T iron with saw cuts therein at the bending points, 25 from which I form my joining member.

Fig. 2 is a perspective view of a length of T iron bent to form a joining member.

Fig. 3 is a side elevation of a length of air duct, partly in section, with my improved joining members in place.

Fig. 4 is a cross-sectional view through an air duct, taken on line 4—4, Fig. 3, looking in the direction of the arrows.

Fig. 5 is an enlarged fragmentary detailed view, partly in section, taken on the line 5—5 of Fig. 3, looking in the direction of the arrows.

Fig. 6 is a cross-sectional view taken through an air duct where two of the walls thereof are plaster board, one is a side or partition wall and 40 one is the ceiling of the building, two methods of securing the air duct to the wall and ceiling being illustrated.

In the drawing, the air duct A is shown in conventional form and may consist of a passage- 45 way formed of four sides of plaster board, as illustrated in Fig. 3, or it may be formed of two sides of plaster board with the ceiling B serving as one side of said passageway and a partition wall C as another side. Also, there could 50 be three sides of plaster board and one side formed by either the ceiling or the partition wall, such arrangement being well understood in the art.

My invention particularly relates to the manner of joining together and supporting the plas-

ter boards at their ends. I preferably employ a material known as "gypsum boards", which are universally sold in commercial practice. I have designated these gypsum boards by the letter D in the drawing. These gypsum boards are of any usual lengths such as are marketed commercially, and they are adapted to have plastering normally applied thereto.

In Fig. 1 I show a length of T iron 1, in the web member 2 of which I have placed saw cuts 3 which extend through said member to the flange member 4. These cuts 3 are placed at the point where the T iron 1 is to be bent.

In Fig. 2 I have shown the T iron 1 in bent position to illustrate how the web member 2 appears after the bending operation is completed. The web sections 2 serve as division members between the ends of the gypsum boards D. In these web sections 2 I provide perforations 5 to receive nails 6, which have enlarged heads 7, for a 20 purpose to be described.

In the structure illustrated in Fig. 3 the gypsum boards D have a surface adapted to receive plaster which adheres tenaciously thereto. These gypsum boards are of suitable lengths and are 25 cut straight across at their ends. When the gypsum boards are to be assembled to form an air duct unit such as is illustrated in Fig. 3, the top and bottom boards extend across the side boards so that nails 6 may be driven through the 30 top and bottom boards into the edges of the side boards, and thereby hold said structure thus formed in a compact, rectangular form. The ends of the gypsum boards D are then passed over the flange member 4 and abut against the 35 web member 2. The nails 6 are then inserted through the perforations 5 in the web members 2 and may be driven through said perforations sufficiently to cause the heads 7 of said nails 6 to gouge through the surface of the gypsum 40 boards D. By this means a gripping action on the boards D is obtained by the nails 6. This action is clearly shown in the enlarged detail view of Fig. 5.

The nails 6 are shown in Fig. 3 with heads 7 45 alternating along the web member 2 with the points of said nails so as to force the wall members D into close contact with the flange 4 and web 2 of the joining member E.

Any appropriate means for supporting the duct 50 shown in Fig. 3 may be employed, such as rope or chain hangers or brackets. I have illustrated two methods of support in Fig. 6. In the upper or ceiling structure B I have employed an anchor 9 placed in said ceiling, a bracket 10 on the join- 55

ing member E, and a bolt or screw 11 adapted to secure an upper corner of the duct A to said ceiling. At the lower right-hand side of said drawing in Fig. 6 I have illustrated a plug 12 adapted 5 to be placed in the partition wall C and appropriately secured to the duct A by wire loops 13.

The T iron supporting member E is highly effective for the purpose for which I employ it, and reduces the cost of constructing air ducts of this 10 type considerably, both in labor and material. When plastered these air ducts present a pleasing appearance and are very efficient in operation.

I claim:

A joint for an air duct, formed of individual

wall members, comprising a joining metal member of the shape having a web and a flange member, said flange member supporting the ends of said individual wall members and which ends abut against the web members, said web member being perforated to receive nails each having a head and a point for holding said wall members in contact with said web and flange members, said nails being passed through said perforations with heads and points alternating 5 about said joint, said web members being cut transversely at intervals so said flange members can be bent at said cut portions.

CHARLES W. FAWCETT.
